(57) **CLAIM**

The ornamental design for a water proof case for a portable electronic multimedia communications device, as shown and described.

DESCRIPTION

FIG. 1 is a perspective view of a water proof case for a portable electronic multimedia communications device according to the present invention.

FIG. 2 is a front view of the water proof case for a portable electronic multimedia communications device of FIG. 1.

FIG. 3 is a rear view of the water proof case for a portable electronic multimedia communications device of FIG. 1.

FIG. 4 is a left side view of the water proof case for a portable electronic multimedia communications device of FIG. 1.

FIG. 5 is a right side view of the water proof case for a portable electronic multimedia communications device of FIG. 1.

FIG. 6 is a top view of the water proof case for a portable electronic multimedia communications device of FIG. 1.

FIG. 7 is a bottom view of the water proof case for a portable electronic multimedia communications device of FIG. 1.

FIG. 8 is a reference view of the water proof case for a portable electronic multimedia communications device of FIG. 1, the letters and indicating lines of which do not form ornamental design; and,

FIG. 9 is another reference view of the water proof case for a portable electronic multimedia communications device of FIG. 1, the letters and indicating lines of which do not form ornamental design.

The broken lines showing a phone are for the purposes of illustrating environment and form no part of the claimed design.
